UNITED STATES PATENT OFFICE

164,657

TOY PISTOL

Allen Dix Tovell, Pasadena, Calif.

Application June 16, 1951, Serial No. 15,568

Term of patent 3½ years

(Cl. D34—15)

To all whom it may concern:

Be it known that I, Allen Dix Tovell, a citizen of the United States of America, residing in Pasadena, county of Los Angeles, and State of California, have invented a new, original, and ornamental Design for a Toy Pistol, of which the following is a specification, reference being had to the accompanying drawing, forming part thereof.

Fig. 1 is a top plan view of a toy pistol, showing my new design.

Fig. 2 is a side elevational view thereof.

Figs. 3 and 4 are front and rear elevational views, respectively.

The opposite side of the pistol is the same as the side that is illustrated.

I claim:

The ornamental design for a toy pistol, substantially as shown and described.

ALLEN DIX TOVELL.
